United States Patent

Des. 240,622
Patented July 20, 1976

240,622

INDEXING TAB

Kenneth E. Thornton, Rte. 1, Box 345,
Colton, Oreg. 97017

Filed Sept. 27, 1974, Ser. No. 510,044

Term of patent 14 years

Int. Cl. D19—99

U.S. Cl. D19—99

Fig. 1.

Fig. 2.

Fig. 6.

Fig. 5.

Fig. 4.

Fig. 3.

Fig. 7.

FIG. 1 is a perspective view of an indexing tab showing my new design;

FIG. 2 is a bottom rear perspective view thereof;

FIG. 3 is a reduced scale front elevational view;

FIG. 4 is a top plan view thereof;

FIG. 5 is a rear elevational view thereof;

FIG. 6 is a bottom plan view thereof; and

FIG. 7 is a left end elevational view.

I claim:

The ornamental design for an indexing tab, as shown and described.
